C. FISCHER

CHAIR TIGHTENER

Filed April 5, 1922

Patented July 17, 1923.

1,461,868

UNITED STATES PATENT OFFICE.

CHARLES FISCHER, OF COLDWATER, OHIO.

CHAIR TIGHTENER.

Application filed April 5, 1922. Serial No. 549,781.

To all whom it may concern:

Be it known that I, CHARLES FISCHER, a citizen of the United States, residing at Coldwater, in the county of Mercer and State of Ohio, have invented certain new and useful Improvements in Chair Tighteners, of which the following is a specification, reference being had to the accompanying drawings.

10 This invention relates to certain improvements in chair tighteners and it is an object of the invention to provide a device of this general character having novel and improved means whereby a chair may be maintained rigid and at the same time effectively braced to offset extreme or rough usage.

Another object of the invention is to provide a novel and improved device of this general character which is operatively engaged with the seat of the chair and the supporting members or legs therefor and in a manner to effectively brace or reinforce the chair structure and at the same time to maintain the parts of such structure in a 25 tightened condition.

Furthermore, it is an object of the invention to provide a novel and improved device of this general character adapted to be operatively engaged with the seat of 30 a chair structure and with the supporting members or legs together with tensioning means whereby the legs are held tightened, said device when applied also serving to strengthen or reinforce the seat structure.

35 The invention consists in the details of construction and in the combination and arrangement of the several parts of my improved chair tightener whereby certain important advantages are attained and the device rendered simpler, less expensive and otherwise more convenient and advantageous for use, as will be hereinafter more fully set forth.

The novel features of my invention will 45 hereinafter be definitely claimed.

In order that my invention may be the better understood, I will now proceed to describe the same with reference to the accompanying drawings, wherein:

50 Figure 1 is an elevational view of a chair structure showing a tightener applied thereto constructed in accordance with an embodiment of my invention,

55 Figure 2 is a view in bottom plan of the structure as illustrated in Figure 1,

Figure 3 is a longitudinal sectional view

on an enlarged scale taken through my improved tightener, certain of the parts being in fragment,

Figure 4 is a view in perspective of the 60 plate adapted to be secured to the chair seat, and

Figure 5 is a view in perspective of the second plate herein disclosed.

As disclosed in the accompanying drawing S denotes the seat of a chair structure having associated therewith the supporting members or legs L of a conventional type.

Secured to the under surface of the seat S is an elongated metallic plate 1, said plate 70 being secured to the seat S through the instrumentality of the screws 2 or the like. This plate 1 when applied also serves to strengthen or reinforce the seat.

At its center portion the plate 1 is provided with an opening 3 through which is disposed a headed shank or bolt 4, the head a of said bolt being above the plate 1, said head being preferably of a tapered form and snugly received in the opening 3.

5 denotes a second plate of a relatively short length and which is provided with a center opening 6 through which the threaded shank 4 is freely disposed. Threaded upon the shank 4 below the plate 5 is a wing nut 7 or the like which maintains the plate 5 against displacement and is operated to force the plate 5 toward the plate 1 as the necessities of practice may require.

Each end portion of the plate 5 is provided with two transversely spaced openings 8 and freely disposed through each of said openings is a rod 9. One end portion of the rod 9 is provided with a head 10 to engage or contact with the plate 5 from above and of a diameter greater than the diameter of the opening 8. The opposite end portion of the rod 9 is engaged with an eye screw 11 which is fastened to a supporting member or leg L at a desired point 90 thereon.

With my improved device applied and by proper turning of the nut 7 the plate 5 is forced toward the plate 1, resulting in tension being imposed upon the rods 9, the pull imposed upon the supporting members or legs L maintaining said legs and the structure associated therewith in a tightened condition. The device when applied also serves to strengthen or reinforce the chair structure.

100 Adjacent the opposite end thereof, the

plate 5 is provided with the openings 12 aligned longitudinally of the plate 5 and with the openings 6. Freely disposed through the openings 12 are the arms 14 depending from the plate 1 and which arms 14 serve to hold plate 5 against turning movement and thereby assuring the maintenance of said plate in proper position.

As herein disclosed, the arms 14 are struck out from the plate 1 and pressed or otherwise bent into desired position.

From the foregoing description it is thought to be obvious that a chair tightener constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. In combination with the seat and the associated supporting members of a chair structure, a plate secured to the under surface of the seat, a member depending from said plate, a second plate having an opening through which the member is freely disposed, a nut threaded upon the member below the second plate, means carried by the first named plate and co-acting with the second plate to hold the second plate against turning movement, and members connecting the second plate and the supporting members of the chair structure.

2. In combination with the seat and the associated supporting members of a chair structure, a plate secured to the under surface of the seat, a member depending from said plate, a second plate having an opening through which the member is freely disposed, a nut threaded upon the member below the second plate, arms depending from the first plate and co-acting with the second

plate to hold the second plate against turning movement, and members connecting the second plate and the supporting members of the chair structure.

3. In combination with the seat and the associated supporting members of a chair structure, a plate secured to the under surface of the seat, a member depending from said plate, a second plate having an opening through which the member is freely disposed, a nut threaded upon the member below the second plate, arms depending from the first plate and freely disposed through the second plate to hold the second plate against turning movement, and members connecting the second plate and supporting members of the chair structure.

4. In combination with a seat and the associated supporting members of a chair structure, a plate secured to the under surface of the seat, a member depending from said plate, a second plate having an opening through which the member is freely disposed, a nut threaded upon the member below the second plate and engageable therewith, arms depending from the first plate at opposite sides of the member, said arms being freely disposed through the second plate to hold the second plate against turning movement, and members connecting the second plate and supporting members of the chair structure.

5. In combination with the seat and the associated supporting members of a chair structure, a plate secured to the under surface of the seat, a member depending from said plate, a second plate having an opening through which the member is freely disposed, a nut threaded upon the member below the second plate, depending arms struck from the first plate and co-acting with the second plate to hold the second plate against turning movement, and members connecting the second plate and the supporting members of the chair structure.

In testimony whereof I hereunto affix my signature.

CHARLES FISCHER.
